UNITED STATES PATENT OFFICE

ROAL DOS SANTOS, OF HONOLULU, TERRITORY OF HAWAII

UMBRELLA

Application filed August 7, 1929. Serial No. 384,009.

This invention relates to an improved umbrella adapted for general utilitarian purposes and it is especially made with the view in mind of constructing an article of this class which is characterized by greater compactness and convenience in arrangement of details.

The purpose of the invention is to provide an economical, dependable and efficient umbrella which is distinguishable in that it includes the structural arrangement of parts which makes for the provision of a satisfactory shade when expanded and in use and additionally satisfactory parcel or package when folded.

In accordance with the invention, I provide a simplified umbrella of this class which comprises a telescoping handle which may be extended for carrying purposes, collapsed for storage purposes, said structure being further rendered unique in that it includes foldable sectional ribs and a foldable covering therefor whereby to provide a complete umbrella which may be collapsed or folded into such a small space as to permit it to be conveniently carried in a hand bag, or even in one's pocket, thereby rendering it accessible for frequent use.

Other features and advantages and the specific details and their relative association and arrangement will become more readily apparent from the following description and drawings.

In the drawings:

Figure 1 is a sectional view, the covering being removed, showing the frame work and handle construction.

Figure 2 is a view showing the umbrella completely folded for carrying purposes, the covering material being omitted for clearness of disclosure.

Figure 3 is an elevational view of a casing in which the folded umbrella is placed for carrying, this being in the nature of a comparatively small hand bag.

Figure 4 is a cross sectional view through the handle construction.

Figure 5 is a fragmentary sectional view of a portion of one of the sections of the handle.

The reference character 8 in Figure 1 designates the handle, and this is made of telescopic construction and embodies graduated sections, the upper one of which is designated by the reference character 9, the lower one by the reference character 10, and the intermediate one by the reference character 11. These are of proportions to permit them to be telescoped into the folded or collapsed state represented in Figure 2 or to be extended to carrying position as shown in Figure 1. The sections 9, 10 and 11 are of tapered tubular form and the uppermost section is provided at its top with a cap and below this with a collar 13, having outstanding arms 14. Then, at the point 15 is a conical stop or shoulder. The reference numeral 16 designates the metal ferrules and reference numeral 17 designates the retaining pin, forced outwardly by coil springs 18 as shown in Figure 4. These are retaining pins and serve to hold the sections of the handle in extended position. In this connection it will be noted in Figure 5 that the sections of the handle are formed with diametrically opposed tapered notches or grooves as at 19 and by aligning the pins with these grooves and forcing the sections of the handles together, it is obvious that the cam action will cause the pins to be retracted against the tension of the spring and allow the sections of the handle to be telescoped into the folded space already described.

A plurality of radial ribs, generally designated by the reference characters 20 are provided for maintaining the usual covering material. The covering material may be of any appropriate texture and it is obviously fastened to the ribs in a customary or convenient manner. These ribs are made of channel shaped sections 22 and 23, the sections being pivoted together at their adjacent ends as at 24. The reference numeral 25 clearly designates a slidable retaining sleeve which serves to fasten the joint to hold the sections in alignment when the ribs are in use. The sleeve, however, may be slipped out of retaining position to permit the sections to be folded into the folded relationship seen in Figure 2.

The inner sections 22 are pivotally connected to the arm 14 of the aforesaid collar 13.

The reference characters 26 designate the foldable braces or stays which are pivoted at their outer ends to the pivoted sections 22 of the ribs, also pivoted at their inner ends to a tapered conical retainer 27. This slidable retainer is adapted to be forced down in firm frictional engagement with the aforesaid stop shoulder 15 as seen in Figure 1 to hold the ribs out in expanded or umbrella forming relationship. It will thus be seen that by extending the handle to the position seen in Figure 1, sliding the retainer 27 down on the shoulder 15, the inner section 22 of the ribs will be expanded.

Then the outer sections are locked in place by adjusting the retaining sleeves 25 over the projecting ends of the inner sections. As the handle sections are pulled out, the retaining pins 17 are automatically snapped into retaining position, thus holding the handle assembled.

The reference character 28 merely designates the hand bag casing into which the completely folded umbrella is placed for pocket or hand bag carrying purposes. Figure 1 shows the expanded state and the details of Figure 2 show the folded state.

A careful consideration of the description in connection with the drawings will enable the reader to obtain a clear understanding of the construction, method of use and the features and advantages of a compact and convenient foldable umbrella of the type stated. Therefore a more lengthy description is believed unnecessary.

Minor changes in the shape, size and rearrangement elements coming within the field of invention claimed may be resorted to, in actual practice, if desired.

I claim:

In a collapsible umbrella, a telescoping sectional handle having a pair of opposed pins 45 radially and slidably mounted in the inner end of the smaller section, spring means engaging the pins to normally urge the same outward for engagement with the edge of the outer end of the larger section, said larger 50 section having opposed notches in its inner wall at its outer end, said notches having inclined bottom walls merging into the inner wall of the larger section, said sections adapted to be turned relatively one to the 55 other to register the pins with said notches whereby collapsing pressure on the sections moves said pins over said inclined bottom walls and retracts said pins into the larger section.

In testimony whereof I affix my signature.
ROAL dos SANTOS.
